UNITED STATES PATENT OFFICE.

ALBERT B. FUHR, OF MACOMB, ILLINOIS.

WINDOW-VENTILATOR.

1,309,886.

Specification of Letters Patent. Patented July 15, 1919.

Application filed August 22, 1918. Serial No. 250,975.

To all whom it may concern:

Be it known that I, ALBERT B. FUHR, a citizen of the United States of America, residing at Macomb, in the county of Mc-
5 Donough and State of Illinois, have invented certain new and useful Improvements in Window-Ventilators, of which the following is a specification.

This invention relates to certain new and 10 useful improvements in window ventilators and has among its main objects to provide a device of this character which is extremely simple in plan of construction, although effective in operation as well as durable and 15 cheaply and easily manufactured.

A further object of the invention is to provide a window ventilator which may be readily secured in position and which is provided with a plurality of movable glass 20 panels having a novel and improved operating means connected therewith, suitable means being provided to retain the operating means in adjusted positions so as to vary the ventilating effects obtained.

A still further object of the invention is 25 to provide a ventilator which will not very materially prevent the view of objects outside of a dwelling from the interior thereof and which includes a plurality of movable panels which may be opened if desired to obtain the desired ventilation although the breeze may be moving from different directions.

With the above general objects in view 30 and others that will become apparent as the nature of the invention is better understood, the same consists in the novel construction, form and arrangement of parts, hereinafter more fully described, shown in 35 the accompanying drawing and claimed.

In the accompanying drawing forming part of this application, wherein like characters of reference refer to corresponding parts throughout the several views,

40 Figure 1 is a perspective view of the present invention shown in its operative position from the outside of a dwelling;

Fig. 2 is a sectional view taken substantially on line 2—2 of Fig. 1 and showing 45 in dotted lines several positions of the panels and the manner in which the adjusting arms are arranged;

Fig. 3 is a fragmentary detail view of one 50 of the adjusting arms with the locking hand wheel or nut therefor;

Fig. 4 is a fragmentary detail view of a portion of one of the panels;

Fig. 5 is a sectional view taken substantially upon the line 5—5 of Fig. 2; and

Fig. 6 is a sectional view taken substantially upon line 6—6 of Fig. 3.

Referring more in detail to the several views, the present invention contemplates the provision of a frame-like casing preferably formed of sheet metal, including parallel front and rear lower angle members 5 and 6, respectively, which are connected by lower side angle members 7 to thus form a substantially rectangular open portion at the lower end of the frame. A suitable bottom member 8 in the form of a panel is arranged upon the horizontal flanges of the bars 5, 6 and 7 and is provided with a substantially rectangular central opening 9, which is closed by a removable panel 10 provided with a knob 11 to be grasped when removed.

At each corner of the rectangular frame portion formed by the bars 5, 6 and 7 is secured the lower ends of upright corner angle bars 12, 13, 14 and 15, which are suitably connected substantially midway between their ends by a horizontal bar 16 at the front of the frame and by side bars 17 and 18.

The upper ends of the bars 12 and 13 are connected by a horizontal bar 19 and the bars 12 and 15 have their upper ends connected by a rearwardly upwardly inclined bar 20 which is similar to the bar 21 which connects the upper ends of the bars 13 and 14.

The spaces between the bars 7, 17 and 20 at one side of the device are closed by suitable horizontally swinging hinged glass panels 22 which are similar to the panels 23 which close the spaces at the opposite end of the device between the bars 7, 18 and 21.

The spaces between bars 5, 16 and 19 are closed by glass panels 24 and 25 which are suitably hinged at their upper longitudinal edges respectively to the bars 16 and 19 so as to swing rearwardly and upwardly, as clearly indicated in Figs. 1 and 2.

An inclined glass panel 26 is hinged at its lower forward longitudinal edge 27 to the bar 19 to close the space at the top of the device and whereby the panel 26 may be swung upwardly and forwardly to an open

position as shown in Fig. 2. Suitable turn buttons 28 are provided for the panels 22 and 23 to maintain the same closed.

In order to operatively swing the panels 24, 25 and 26 from a point within a dwelling provided with the window casing A so as to open or close said panels, suitable adjusting arms are provided for each of the panels and as each of said arms are of similar construction, it is believed that description of one of the same will suffice. Also, the means for retaining the adjusting arms in their different positions is identical in each instance and description of only one of the same will 15 also be described. As shown in Fig. 4, the panel, such as panel 24, is provided with a metal binding or edge protecting strip 25' to which is secured a pivot lug 26' adapted for connection to the free end 29 of the link 20 30 of the adjusting arm, which link 30 is in turn pivotally connected as at 31, to a second link 32 of the adjusting arm. The inner or free end of the link 32 is pivotally mounted upon the shank of the bolt 33 which 25 is suitably fastened to the adjacent inside face of the window frame A by suitable screws 34. A hand wheel or nut 35 is threaded upon the bolt 33 and has a hub portion 36 adapted to frictionally engage the 30 adjacent portion of the link 32 so as to effectively maintain the link 32 against pivotal movement to thereby maintain the panel connected thereto in its opened or closed adjusted position.

35 It is to be understood that, as clearly indicated in Fig. 2, the links 30 and 32 are substantially in the form of toggle levers which are broken to open the panels 24 and 25 which swing inwardly and which are 40 straightened to open the panel 26 which swings outwardly.

From the foregoing description, it is believed that the construction and operation of the present invention is readily understood, 45 it being noted that the panel 10 may be removed at any time to receive articles therethrough from a person outside of a dwelling and for any purpose to which the same may be put, while if the breeze is blowing toward 50 that side of the device which is situated at the right hand side of Fig. 1, the panels 22 may be opened to allow the breeze to enter the window and the room provided therewith. On the other hand, if the breeze is 55 blowing in the opposite direction panels 22 may be closed and the panels 23 opened for like results.

In case the breeze is blowing directly toward the panels 24 and 25, the same may be 60 opened and in order to insure for proper escape of warm air the panel 26 may be

opened, it being a well established fact that the heated air will be most abundant at the top of the ventilator.

As practically the entire present device is 65 formed like a show-case of glass panels, the same does not in any way obstruct the view of persons from the inside of the dwelling and does not detract from the neat appearance of the dwelling equipped with the 70 same.

The adjusting arms may be readily swung to the desired positions with little effort as well as quickly secured in such positions by manipulation of the wheels or nuts 35 and 75 the links 30 and 32 are positioned so as to be entirely out of the way when in use.

Any suitable means may be provided to attach the present device in position, but as the same does not form part of the present 80 invention, no mention of a specific means therefor is made.

While the form of the invention herein shown and described is what is believed to be the preferred embodiment thereof, it is 85 nevertheless to be understood, that minor changes may be made in the form, combination and arrangement of parts without departing from the spirit and scope of the 90 invention as claimed.

What I claim as new is:

1. A window ventilator including a frame-like casing, an inwardly and upwardly swingable panel in the front of said casing normally disposed in a vertical plane 95 when closed, manually operable means to open said panel including a pivoted link, and means to maintain said link against pivotal movement to retain the panel in adjusted open positions.

2. In a window ventilator, a hinged panel, a link having one end pivotally connected to said panel, a second link having one end thereof pivotally connected to the other end of the first named link, a frame, a bolt fastened to said frame, said second link having its other end pivotally mounted on said bolt, and a nut threaded on said bolt adapted to frictionally engage the adjacent end of the second link to maintain the same against 105 pivotal movement to thereby retain the panel in open adjusted positions.

3. A window ventilator including a frame, upper and lower hinged glass panels in the front of said frame, said panels being inwardly swingable to open positions, an outwardly swingable inclined glass panel in the top of said frame, and means to adjustably maintain said panels in open positions.

In testimony whereof I affix my signature. 120

ALBERT B. FUHR.
